UNITED STATES PATENT OFFICE.

EDWARD JAMES KENNEDY, OF NEW YORK, N. Y.

MECHANISM FOR ELECTRICALLY CONTROLLING AND OPERATING FARE-REGISTERS AND OTHER DEVICES.

1,090,215.

Specification of Letters Patent. Patented Mar. 17, 1914.

Application filed April 10, 1913. Serial No. 760,296.

To all whom it may concern:

Be it known that I, EDWARD JAMES KENNEDY, a citizen of the United States of America, residing in the borough of Brooklyn, city of New York, county of Kings, in the State of New York, have invented certain new and useful Improvements in Mechanism for Electrically Controlling and Operating Fare-Registers and other Devices, 10 of which the following is a specification.

The present invention, while relating generally to fare registers, has particular reference to improvements in electrical operating means therefor, such means being additional 15 to and capable of use in connection with the means now commonly employed for operating fare registers manually.

The object of the invention is to facilitate the control and operation of fare registers 20 by providing them with electrical actuating mechanism responsive to one or more conveniently located push-buttons.

A further object is to assemble the register and its actuating and controlling mechanism in such relation, as to permit either or both to be readily removed and replaced, or substitution made without in any way disturbing the register-supporting bracket and the circuit connections thereon, which 30 bracket is designed to be mounted as a fixture for continued and uninterrupted use but may be removed at any time for examination, repair, or other purpose, should occasion require it.

35 A further object is to cause both visual and audible signals to be given as each fare is registered, in order to indicate that the register has completed its operation and that the push button may be released.

40 A further object is to provide for successively registering any desired number of fares by pushing a button and holding it pressed until signals are given back indicating that the register has operated the required number of times.

45 Mechanism suitable for carrying my invention into effect is illustrated in the accompanying drawings. I wish it understood, however, that I do not limit myself to either the exact form or construction shown, as various changes may be made therein without departing from the spirit and scope of the present invention.

50 In the drawings—Figure 1 is a front view of the fare register complete. Fig. 2 is a

side view thereof. Fig. 3 is a front view of the permanent supporting-bracket on which the register and its actuating mechanism are removably mounted. Fig. 4 is a view of the rear face of the casing containing the register actuating mechanism, which rear face is designed to be fitted against the supporting-bracket shown in Fig. 3. Fig. 5 shows the rear face of the well known standard single fare register. Fig. 6 is a front elevation of my improved mechanism for operating the fare register electrically, a portion of the casing being shown broken away. The rear face of the fare register illustrated in Fig. 5 is adapted to be fitted on and serves as a cover for the casing of the mechanism here shown. Fig. 7 is a view of the diagram of my improved mechanism, showing the same in its normal position. Fig. 8 is a similar view, showing the position and relation of the parts the moment after a fare is registered.

Referring now to the drawings, 1 represents a standard single fare register of a form well known in the art and in common 50 and general use. This particular type of register is here employed for purposes of illustration only and as it forms no part of the present invention, a description of its mechanism will not be given. It suffices to say that it is contained in a suitable casing 2, and thus inclosed is secured in position by bolts 3, 3 and a screw 4. The preliminary setting of the register, by turning the trip mechanism back to indicate zero, is effected 55 in the usual manner by means of a projecting shaft 5 which is suitably headed for convenience in rotating it. As is well known, the trip mechanism of such a register is responsive to the oscillation of a rock-shaft 6 (shown in Fig. 5) which is provided on its projecting end with a crank-arm 7 carrying a stud 8. The stud extends parallel to the rock-shaft 6 and forms, in effect, an off-set continuation thereof. The mechanism of the 60 register is of such construction and arrangement as to visually indicate in the usual manner, at 9, on the face thereof, each operation in registering a fare and at the same time give an audible signal by sounding a bell 10 (shown in Fig. 5).

As previously stated, the register above described, is a standard form, well known in the art, and being here employed for convenience only in illustrating the application 110

of my improved actuating mechanism, it will be understood that the present invention is not limited to use with this particular type of register and that any other form may be substituted, if desired.

Referring now to Figs. 6, 7 and 8, which illustrate my improved mechanism, 11 represents a suitable casing or housing in which the mechanism is contained, the same being made up as an iron casting to form the magnetic field of a solenoid 12. Any suitable source of electricity may be employed for operating my improved mechanism, such as storage batteries or the current taken from either an overhead trolley or a third rail. The armature 13 of the solenoid 12 is connected to transmit its motion to a shaft 14, which latter, when the fare register is secured in position, becomes alined with the rock-shaft 6 of the register, thus bringing the off-set or stud 8 of the register shaft into operative relation to be engaged by a crank-arm 15 fast on the shaft 14 and given movement necessary to oscillate the rock-shaft and operate the register. (See Figs. 7 and 8.) The solenoid armature 13 is connected with the shaft 14 through a link 16, lever 17 pivoted at 18, expansion reach-rod 19 and crank-arm 20, fast on the shaft and the several members forming this connection are yieldingly maintained in the position shown in Figs. 6 and 7, with the solenoid armature elevated, by a retractile spring 21. Stops 22 and 23, preferably of rubber, serve to limit the movement of lever 17.

As arranged the fare register may be operated electrically, by energizing the solenoid or manually, through the same system of levers, by pulling down the rod 24, which is attached to the solenoid armature. In either case, the spring 21 will act to return the parts to normal position.

In operating the register electrically, as above described, it is desirable to provide means for causing the mechanism to repeat automatically for as many fares as are to be registered at any one time and for this purpose I employ a repeating switch, which will operate continuously, under control, to open and close the circuit through the solenoid as often as desired, the switch being timed in its action to permit each operation of the register to be fully completed before breaking the circuit and deenergizing the solenoid, as the preliminary step to the next operation in registering another fare.

The switch is mounted on a base 25 of insulating material and consists of two arms 26 and 27, one (26) being pivoted at 28 and the other (27) pivoted at 29. The switch arm 26 is limited in its movement by two stops 30 and 31 which also serve as contacts for the switch arm being formed by projections of a casting 32, on which the arm is pivoted. A link 33 between the casting 32 and

a binding post 34, connects the casting in the power circuit, which will be later on described.

35 represents a spring, which when free to act, operates to throw the arm 26 downward against the stop 31, the purpose of giving this arm the above described limited movement being to obtain a wiping or rubbing contact between the engaging faces of the switch members and thus keep them clean and free of corrosion or dirt.

The opening and closing of the repeating switch is effected indirectly by the movement of the solenoid armature, motion being transmitted from it through the lever 17, reach-arm 36 and double crank-arm 37. The crank-arm 37 turns loosely about the pivotal center of the switch arm 27, to which latter the crank-arm 37 is connected by twin springs 38. The arrangement of these springs is such that as the solenoid is energized and the armature thereof is drawn downward, motion will be transmitted through the connection described, to change the line of pull or the relation of the springs 38 to the pivotal center of the arms 27 and 37, to which the ends of the springs are attached. Normally, as shown in Fig. 6, the springs act to maintain the switch closed but when the mechanism is thrown into operation, the double crank-arm 37 is given motion necessary to carry the end 39 of the springs over the line of centers 40-40, and thereupon the action of the springs changes and their tendency is then to draw the arm 27 downward or away from the arm 26 and open the switch.

In order to maintain a closed circuit through the switch while a fare is being registered and until signals are given back to indicate that the operation, in each instance, has been completed, the above stated tendency of the springs 38 to open the switch is checked temporarily by a locking device, arranged to cooperate with the switch-arm 27. The locking device consists of a lever 41, pivoted at 42 and provided with a tooth or projection 43 designed to interlock with a stud, lug or toe 44 formed on or secured to the end of the switch-arm 27. A spring 45, coiled about the pivot 42 of the lever 41 acts to force the lever upward, causing the projection 43 to engage the stud 44 and maintain the switch-arm 27 normally locked. The release is brought about by the attaching post 46, for the end 39 of spring 38, engaging and depressing the free end of the lever 41, until the projection 43 thereof clears the stud 44 on the switch-arm and thereupon the springs 38 act to throw the arm and open the switch (see Fig. 8), which results in breaking the circuit, deenergizing the solenoid, and permits the mechanism to be returned to normal position. At that stage of the operation when the switch-arm 130

releasing device begins to act, the solenoid armature is nearing the limit of its downward movement and the register having at that time completed its operation, further rotation of the shaft 14 is positively checked by the register mechanism. Thereafter, continued movement of the solenoid armature to the end of its stroke is permitted and provided for in the construction and employment of the extension reach-rod 19, the spring 47 of which is compressible to an extent sufficient to permit the armature to complete its stroke, which motion, following the operation of registering a fare, is utilized to effect the release of the switch arm and open the circuit, as above described. In the return of the mechanism to normal position, the re-shifting of the spring 38 over the line of centers 40-40, causes it to act to close the switch, the arm 27 of which again becomes locked thus closed, by the upward movement of the locking lever under the influence of its spring and if now the operator continues to hold the push-button pressed down, the entire operation as above described will be repeated and another fare registered and this will continue until the button is released.

The metallic circuit for the passage of current from the binding-post 34 is provided by way of the link 33, casting 32 with its contacts 30, 31, switch-arms 26, 27, brush 48, casting 49, wire 50, solenoid 12 and wire 51 to a second binding post 52. The brush 48 is secured to the casting 49 and its free end 53 bears on a boss or hub 54 of the switch-arm 27. The purpose of employing such a brush is to make the flow of current direct from the switch-arm to the casting and thus relieve the bearings of the several arms mounted in the casting from carrying current.

The bolts 3, 3, and screw 4, above referred to, serve to secure the fare register and its actuating mechanism together in operative relation and thus assembled, the register acts as a cover for the open front of the casing in which the actuating mechanism is contained, as shown in Fig. 2.

In mounting the register and its attached actuating mechanism in a car, for example, a bracket or base-casting 55 is employed which is designed to be permanently secured in position as a fixture by bolts, screws or in any other suitable manner. The bracket is provided circumferentially with a flange 56, against which the casing 2 of the register actuating mechanism seats and is removably held in position by fastenings at the top and bottom. The top fastening is in the form of a projection 57 from the flange 56 which enters an opening in a lug 58 on the casing 2. At the bottom, the fastening takes the form of a fixed staple 59, on the base-plate, which projects through an opening formed in a lug

60 of the casing 2 and is engaged by either or both a pivoted hook 61 and a pad-lock (not shown). Circuit leads 62, 63 are brought in from the rear of the bracket, through an opening 64 and terminate in spring contacts 65, 65, which are mounted on an insulated plate 66, secured to the brackets. The spring contacts 65, 65 are designed to cooperate with binding posts 34 and 52, which project through openings in and are insulated from the casing 2. (See Fig. 4).

The construction and operation of the actuating mechanism can be more readily seen from Figs. 7 and 8, which show the same diagrammatically and for clearness of illustration, omit many details. As the arrangement of the circuit or circuits and the number and location of the push-buttons are unimportant and may be changed at will to adapt the same to the particular use to which the register is put, it will be understood that the showing here is illustrative only.

The operation as well as the many advantages of the present invention will be apparent from the foregoing and further description will therefore not be given.

Having, therefore, described my invention, I claim:

1. Means for operating a fare register comprising a solenoid, the armature of which is adapted to be given motion either manually or electrically, and requisite connections including a series of push buttons for controlling the operation of the solenoid from distant points.

2. The combination of a fare register, a push button, and interposed means controlled by the push button and adapted to operate the fare register repeatedly under continued pressure on the button.

3. The combination with a fare register, of means for electrically operating the register, the said means including mechanism for causing the register to automatically repeat its operation for any number of fares.

4. The combination with a fare register, of means for electrically operating the register, the said means including an automatic repeating switch controlled by a push button.

5. The combination with a fare register, of electric means controlled by a push button for continuously operating the register for any number of fares, the said means including an automatic repeating switch in circuit with the push button.

6. The combination of a fare register, actuating mechanism for electrically operating the register, requisite circuit connections, a push-button control for the circuit, and means independent of the push-button control for automatically breaking the circuit after the fare register has completed each operation.

7. The combination of a fare register, actuating mechanism for electrically operating the fare register, requisite circuit connections, a push-button control for the circuit, and means independent of the push-button control acting automatically to successively open and close the circuit after the fare register completes each operation.
8. The combination of a supporting member secured as a fixture and having circuit leads terminating therein, a fare register removably secured to said supporting member, and electric actuating mechanism removably interposed between the supporting member and the fare register.
9. The combination of a supporting member secured as a fixture and having circuit leads terminating therein, mechanism for electrically operating a fare register, said mechanism being removably secured to the

supporting member in a manner to automatically connect with the circuit leads therein, and a fare register removably secured in operative relation to the said mechanism.

10. The combination of a supporting member secured as a fixture and having circuit leads terminating therein, mechanism for electrically operating a fare register, the said mechanism being contained in an open front casing removably secured to the supporting member in a manner to automatically connect with the circuit leads therein, and an incased fare register removably secured as a cover to the casing of said mechanism.

EDWARD JAMES KENNEDY.
